UNITED STATES PATENT OFFICE.

WILLIAM E. BURKE, OF LORAIN, OHIO.

STOP AND WASTE OR DRAIN COCK.

1,073,953.

Specification of Letters Patent. Patented Sept. 23, 1913.

Application filed May 3, 1912. Serial No. 695,004.

To all whom it may concern:

Be it known that I, WILLIAM E. BURKE, a citizen of the United States, residing at Lorain, in the county of Lorain and State of 5 Ohio, have invented new and useful Improvements in Stop and Waste or Drain Cocks, of which the following is a specification.

This invention relates to new and useful 10 improvements in stop and waste or drain cocks for use as faucets as well as for application to hydrants and to any other appliances that act on the stop and waste principle.

15 The primary object of the invention is to construct a stop and waste or drain cock wherein each of the functions may be effected independently of the other so that the stop may be completely closed before any 20 waste is possible and thereby intercept the water in the supply pipe from communication with the waste outlet during the operation of the same and also to set up an instant outlet for the waste or drainage at the moment that the stop is closed, and, furthermore, to cut off all possible escape of water 25 through the waste or drainage ports or outlets when the stop is opened.

The improved stop and waste or drain 30 cock in addition to the ordinary essential elements of devices of this class, and including a valve head, comprises what may be termed a compound valve stem composed of parts one of which, at least, is movable relatively to the other and operable by reason of 35 temporary frictional association under certain adjustable conditions to unitedly move in opening and closing the valve head so that when the latter is opened water will 40 be prevented from escaping through the waste or drainage outlets and when the said head is closed it is caused to firmly engage its seat prior to the release of the waste or drainage outlets.

45 The invention also consists in the details of construction and arrangement of the several parts which will be more fully herein-after described and claimed.

In the drawing: Figure 1 is a longitudinal 50 vertical section of a stop and waste or drainage cock embodying the features of the invention and showing the parts of the stem in a position to occlude the waste or drainage outlets and the main valve or valve head 55 closed against its seat. Fig. 2 is a similar view showing the main valve or valve head

closed and the one member of the compound valve stem shifted longitudinally relatively to the other member to open the waste or drainage outlets or ports for the egress of 60 waste or drain water through the valve stem. Fig. 3 is a similar view illustrating the valve or valve head open and the waste or drainage outlets or ports closed by the stem to prevent the water passing through the body of the 65 valve from escaping through the said outlets or ports, a key of particular form being shown applied to the stem in dotted lines. Fig. 4 is a transverse vertical section through the body of the key shown by dotted lines 70 in Fig. 3.

The numeral 5 designates the body of the cock having a partition 6 interrupting the passage therethrough and also provided with an inlet 7 and an outlet 8. The partition 6 75 is formed with an opening 9 around which is a valve seat 10, and in axial alinement with the said valve seat the body 5 has a lateral cylindrical extension 11 interiorly screw-threaded as at 12 to adjustably receive a correspondingly screw-threaded plunger 13 carrying a valve head 15. The valve head 15 has a valve disk 16 mounted on the lower end thereof and shown as held in place by a screw 17, the said valve disk being of 80 suitable material to set up a water-tight engagement with the valve seat 10 when the valve head 15 is adjusted to cause the disk 16 to tightly engage the said seat. The operating means for the plunger 13 and its 85 valve head 15 consists of a compound stem which in part forms the outlet for the waste or drainage and comprises a screw-threaded shank 18 of suitable length and a tubular member 19 through which the said shank 90 extends and provided with an operating handle 20. The tubular member 19 is fully open at its upper end around the shank 18 as at 21 and its lower end has a screw-threaded bore 22 through which the shank 18 projects, 95 the lower end of the member 19 being also provided with an outlet port 23 fully open to a chamber 24 formed in the lateral extension 11 above the plunger 13. The bore of the tubular member 19 has a materially 100 greater diameter than the diameter of the screw-threaded shank 18 so that a clear outlet annular passage is formed in the tubular member around the said shank. The plunger 13 has a port or duct 25 extending there- 105 through and communicating with the chamber 24 and with the outlet extremity of the 110

body 5, the valve head 15 being so shaped and reduced at its juncture with the plunger 13 as to provide an unrestricted passage 26 therearound for the waste or drainage 5 returning into the body 5 through the outlet 8 after the valve head 15 is closed and when the upper outlet extremity of the member 19 is opened.

The upper end of the shank 18 is reduced 10 to form an attaching extremity 27 and has screw-threads in reverse relation to those of the said shank, or if the screw-threads of the shank be of the right-hand character, the threads of the attaching extremity 27 15 will be left-hand, and on the attaching extremity 27 is secured a cap nut 28 having a lower flanged extension 29 formed with a seat 30 in which a rubber or analogous gasket 31 is secured and has its lower face 20 fully exposed around the shank 18 for engagement with the upper flat end 32 of the member 19 to set up a frictional engagement between the upper end of the member 19 and the shank 18 through the gasket 31 so 25 that both members of the compound stem may be caused to unitedly move at intervals or during certain adjustments previous to the release of the waste or drainage through the tubular member 19 in a manner which 30 will be more fully hereinafter explained. The compound stem comprising the shank 18 and tubular member 19 is held in operative association with the lateral extension 11 by a coupling nut or member 33 engaging 35 screw-threads on the upper end of the extension and having therein a suitable packing or washers 34 of any preferred material adapted for the purpose snugly surrounding the tubular member and tightly engaging 40 the upper end of the extension 11 to produce a water-tight joint that will obviate all leakage, particularly around the tubular member. The coupling nut or member 33 is vertically extended at the center as at 35 45 to lengthen the bore or opening therethrough sufficiently to give a stable support to the lower extremity of the tubular member 19 when the latter is adjusted upwardly therethrough and to maintain the port 23 closed, 50 the said port having such inclination that it will be closed at its lower inlet end by the wall of the bore or opening through the coupling nut or member, as clearly shown by Figs. 1 and 3.

55 When the improved stop and waste or drainage cock is disposed below the ground surface or at an elevation and cannot be easily reached for direct manual operation, it is proposed to use the form of key shown 60 by Figs. 3 and 4 and embodying a bifurcated head 36 having a shank or stem 37 removably held therein by a set-screw 38 and provided with a hand bar at its free end extending thereacross. The legs 39 of the 65 head are slotted as at 40 in planes at right

angles to the bifurcation to engage over the opposite members of the handle 20, as shown by Fig. 3, the slots 40 being of a depth sufficient to give a positive hold on the handle members for turning the compound valve stem. The bifurcation in the head 39 is of sufficient depth to give ample clearance for the operation of the parts of the compound valve stem and particularly the cap nut 28 on the shank 18. This key attachment is 70 illustrated to clearly demonstrate that the valve may be operated either by direct manual engagement with the compound valve stem or through the medium of some device adapted to engage the handle 20.

In the operation of the stop and waste or drain cock heretofore described in preferred form, the compound stem has its parts or members moved as a unit when closing the valve head 15 against the seat 10 by the frictional engagement of the upper flat end 32 of the member 19 with the gasket 31, the members 18 and 19 of the stem remaining in association or moving as a unit in a downward direction until the valve head has 85 fully engaged the seat 10, as shown by Fig. 1. It is obvious that when the valve head 15 is seated as shown by Fig. 1, water or other liquid will be prevented from passing through the opening 9 in the partition 6, and the escape of the waste or drainage from the outlet extremity 8 of the body 5 through the ports 25 and 23 and the tubular member 19 will be prevented so long as the gasket 31 is in engagement with the upper 95 end of the member 19. At times it may be desirable to obstruct drainage of the pipe connections to which the stop is attached and under such conditions the members of the compound stem will remain as shown by Fig. 1 and with the port 23 at the lower 100 end of the member 19 closed by the packing or washers 34 by reason of the upward adjustment or position of the tubular member 19. If, however, it is desired to drain the 110 pipe connections with which the stop is associated, the tubular member 19 is independently operated after the valve head 15 has been seated to cause the lower end of said tubular member to extend downwardly 115 into the chamber 24 and clear the port 23 as well as the upper or outlet end of said member, and the waste or drainage then passes upwardly through the port 25 into the chamber 24, through the port 23 and 120 escapes through the tubular member to the exterior of the valve or stop as an entirety.

The drainage adjustment of the parts of the stop is clearly shown by Fig. 2, and it will be observed that the valve head 15 is 125 closely held against the seat 10 so that no water or other liquid from the inlet extremity of the body 5 can pass through the opening 9 in the partition 6 and through the ports 25 and 23, the latter serving under 130

these conditions solely as the egress means for the waste or drainage. In opening the valve head 15 the member 19 is first adjusted upwardly from the position shown by Fig. 2 until the upper flat end 32 thereof engages the gasket 31 to set up a frictional binding relatively to the latter and then the shank 18 may be adjusted with the member 19 by continuing to turn the handle 20 to raise the plunger 13 within the lateral extension 11 and elevate the valve head 15 from the seat 10, as shown by Fig. 3. By first adjusting the member 19 in an upward direction, the port 23 in the lower end thereof is closed by passing upwardly into the bore or opening of the coupling nut 33, and the said port remains in closed condition during the passage of the water or other liquid into the body 5 and through the partition 6 and outlet 8, and hence no leakage will result through the member 19, though some of the water may pass through and above the plunger 13.

It will be understood that the improved stop and waste or drainage cock is particularly adapted for use in freezing temperature to cut off the flow of water, for instance, from a system of pipes and permit the water remaining in said pipes to run outwardly through the cock to overcome the disadvantages and injury to the pipe system incident to the water remaining in the pipes freezing and occluding all bursting of the latter. In seasons or temperatures when freezing of the water will not occur it is unnecessary to drain the cock, and the improved device by the construction hereinbefore explained may be readily adjusted to close the waste or drainage outlets, as shown by Fig. 1, without interfering with the opening and closing movements of the valve head 15. It will also be observed that the essential element or member of the improved cock, consisting of the part 19 of the stem, may be adjusted or moved independently of the valve head 15 and does not require chambering or channeling of the plunger or valve head in order to render it operative and the cost of manufacture is thereby materially reduced and the association of the several parts of the cock is very much simplified. If found necessary substitution for worn parts of the cock by other devices of a similar character may be readily effected at a minimized expense and thus prolong the life of the cock at a comparatively small cost. It will be understood that the disk 16, packing or washers 34 and gasket 31 may be constructed of any material adapted for the purpose and may be readily replaced when worn and rendered unfit for further use. By having the extremity 27 of the shank 18 provided with a screw-thread differing from that of the shank body, the cap nut 28 will be prevented from working loose by the op-

eration of the said shank 18 and member 19 relatively to each other and said cap will be held in one position for positive engagement with the upper flattened end 32 which constitutes an annular face with the gasket 31 to establish frictional binding between the upper end of the member 19 and the shank 18 through the said cap nut 28.

The parts of the stop cock may be modified in their proportions and dimensions to accommodate different applications thereof, and, furthermore, the device as a whole may be disposed as shown in the drawing or in any other position.

What is claimed is:

1. In a stop and waste cock, a body having inlet and outlet with a valve seat between, a valve for said seat having a waste port therethrough, and a compound valve stem associated with said valve and comprising two members one of which is tubular and has a waste port communicating with the interior of the body, one valve member being fixed to the valve and the other movable independently thereof and both members provided with means for causing them to unitedly move.

2. In a stop and waste cock, a body having inlet and outlet with a valve seat between, a valve for said seat provided with a screw-threaded stem, and a tubular member in threaded engagement with the stem for movement endwise upon the same and having a waste outlet adapted to communicate with the body, the said stem and tubular member being provided with means for causing them to move together.

3. In a stop and waste cock, a body having inlet and outlet with a valve seat between, a valve for said seat provided with a screw-threaded stem, and a tubular member adjustable endwise on the stem and having a waste outlet adapted to communicate with the body.

4. In a stop and waste cock, a body having inlet and outlet with a valve seat between, a valve for said seat, a screw-threaded member extending from the valve and constituting part of the stem, a friction device carried at the free end of said screw-threaded member, and a tubular stem member engaging the screw-threaded member and having a waste outlet adapted to communicate with the body, the outer free end of the tubular member adapted to engage the friction device to set up a unitary movement of the screw-threaded and tubular members.

5. In a stop and waste cock, a body having inlet and outlet with a valve seat between, a valve for said seat having a stem member extending therefrom, a tubular member movable on the said stem member and having an outer open extremity and a port at its inner extremity adapted to com-

municate with the body, and a device mounted on the outer end of the said stem member to engage and close the outer open end of the tubular member.

5. 6. In a stop and waste cock, a body having inlet and outlet with a valve seat between, a valve for said seat having a waste port extending through a portion thereof, and a compound valve stem comprising a 10 fixed member associated with the valve and a tubular member movable on the fixed member and having an outer open end and a waste escape port at its inner end adapted to communicate with the body, the outer 15 extremity of the fixed member provided with a frictional device to engage the outer open end of the tubular member to close the latter and also set up frictional engagement therewith to cause the two members to 20 unitedly move.

7. In a stop and waste cock, a body having inlet and outlet with a valve seat between, a valve for said seat having a waste port, and a compound valve stem comprising a 25 threaded member fixed to said valve and a second member in threaded engage-

ment with the first member for movement endwise on the same, one of said members having a waste outlet passage communicating at its lower end with said port and opening at its outer end through that member. 30

8. In a stop and waste cock, a body having inlet and outlet with a valve seat between, a valve for said seat having a waste port, and a compound valve stem comprising a 35 threaded member fixed to said valve and a second member in threaded engagement with the first member for movement endwise on the same, one of said members having a waste outlet passage communicating at its lower end with said port and opening at its outer end through that member, 40 both members being provided with means for causing them to move unitedly.

In testimony whereof I have hereunto set 45 my hand in presence of two subscribing witnesses.

WILLIAM E. BURKE.
